UNITED STATES PATENT OFFICE.

PHILIP J. HAAS, OF YORK, NEBRASKA.

FENCE-POST STAPLE.

1,069,127.

Specification of Letters Patent.

Patented Aug. 5, 1913.

Application filed April 26, 1912. Serial No. 693,480.

To all whom it may concern:

Be it known that I, PHILIP J. HAAS, a citizen of the United States, residing at York, in the county of York and State of Nebraska, have invented a new and useful Fence-Post Staple, of which the following is a specification.

This invention relates to improvements in staples for concrete fence-posts.

10 It has for its object primarily to provide for readily and quickly applying the stringers or horizontal wires to the posts.

A further object is to guard against liability of casualties resulting from lightning-15 flashes.

A still further object is to carry out the aforesaid ends in a simple, effective and expeditious manner.

The invention consists of certain instrumentalities and features substantially as hereinafter fully disclosed and defined by the appended claim.

In the accompanying drawing, illustrating the preferred embodiment of my invention 25 wherein it will be understood that various changes and modifications may be made as to the detailed construction and arrangement of the parts without departing from the spirit thereof, Figure 1 is a

30 view of a fence post with the staple in use. Fig. 2 is a horizontal section thereof. Fig. 3 is a detailed section of the same. Fig. 4 is a detached perspective view of the staple.

In putting my invention into practice, I 35 employ principally a staple 1, which is adapted for use by embedding it partially in the fence-post when in a plastic state, as during the molding operation, the post being designated as 2.

40 The staple is in a continuous piece or length of stout wire, the latter being formed into a central edgewise-disposed loop 3 and duplicate oppositely extended loops 4, 4 in parallel relation one above the other, each

45 being of approximately U-shaped outline, the bottom or curvature of each U being presented outwardly or rather beyond the surface of the post and sufficiently spaced apart to receive between them, a wire stringer or

50 longitudinal member of the fence; this arrangement is duplicated for each longitudinal or fence wire.

A suitable fastening, as a headed pin or key 7, or the like, is inserted into the parallel duplicate loops of the staple, transversely with respect to the fence-wire and serves to secure the latter effectively in place 55 therein.

The inner embedded ends of the staple forming wire are extended laterally into 60 right-angled terminals or portions 5, providing not only for additionally anchoring or securing the staple in the post, but also allowing the bringing or disposing the staple in contact with the metal-reinforce or rods 65 6, commonly incorporated in this type of fence-post and which are usually located or disposed in the corners of the post, for obvious reasons.

It is apparent that this arrangement 70 whereby a metallic conductor is provided between the fence-wire and the metal-reinforce in the form of the wires in the post, having ground-connection, would allow of the grounding of electrical currents resulting 75 from lightning flashes during rainstorms, the moisture or water absorbed by the earth also being promotive, as well understood, of that end, thus guarding against the liability of the destruction of the posts, 80 or buildings, and fatalities to cattle or animals, under the indicated conditions, all of which are appreciated.

What is claimed is:-

A staple, having duplicate loops in parallel relation and a vertical loop directly behind the first mentioned loops with the plane thereof perpendicular to the first mentioned loops, the terminals of the staple being extended laterally therefrom in opposite 90 directions and in a line intermediate of the length of the looped portions, each terminal being in the same horizontal plane as its carrying loop.

In testimony that I claim the foregoing as 95 my own, I have hereto affixed my signature in the presence of two witnesses.

PHILIP J. HAAS.
